UNITED STATES PATENT OFFICE.

WILLIAM S. BECHTOLD, OF NEWARK, NEW JERSEY.

COMB.

Application filed May 24, 1924. Serial No. 715,821.

To all whom it may concern:

Be it known that I, WILLIAM S. BECHTOLD, a citizen of the United States, and a resident of Newark, county of Essex, and State of New Jersey, have invented new and useful Improvements in Combs, of which the following is a full, clear, and exact specification.

My invention relates to combs and refers particularly to combs suitable for employment with short hair.

Combs suitable for retaining the hair in position, or, for purposes of ornamentation usually carry a row of teeth, which, while effective in long hair due to the support given the comb by the curves, or turns, of the hair mass incident to its arrangement, or make-up, these combs are of little and frequently of no value in employment with short hair, especially when the hair is straight and smooth.

Under these conditions, the usual combs of one row of teeth are practically useless, as the short hairs present no holding means for the comb which, hence, can not be retained in place and is useless.

Curved tooth combs have been suggested for this purpose, as have combs with two series of teeth, but none of these are of such construction as to maintain the comb sufficiently for practical purposes, as they present no binding, or holding, means for the hair.

I have found, however, that combs having two rows of teeth staggered with respect to each other, and especially when the teeth of at least one row are curved, will be held firmly by short hair, and that a comb of my construction presents a means whereby a comb may be worn practically as firmly in short hair as the older combs can in long hair.

The present demand for short, or bobbed, hair makes my device of the greatest importance and value, as it allows of the placement and ornamentation of bobbed hair with equal facility and certainty to that of long hair.

In the accompanying drawings, illustrating modified forms of the comb of my invention, similar parts are designated by similar numerals.

Figure 1 is a back view of one form of the comb of my invention, the continuation of the teeth shown being omitted.

Figure 2 is a section through the line 2—2

of Figure 1 illustrating the staggered positions of the teeth of the two series, or rows.

Figure 3 is a section through the line 3—3 of Figure 1.

Figure 4 is a section through a modified form of the comb of my invention.

Figure 5 is a section through another modified form of the comb of my invention.

Figure 6 is a section through still another modified form of the comb of my invention.

The particular form of the device of my invention, shown in Figures 1, 2 and 3, comprises a base 10 carrying a plurality, or row, of undulated teeth 11, 11, 11, having a 70 slightly outward curve 12 and then a downward inward curve 13.

Fixedly attached to the back of the base 10 is a sub-base 14 carrying a plurality, or row, of teeth 15, 15, 15 curved inwardly at 16.

The base teeth 11, 11 and the sub-base teeth 15, 15 are staggered with respect to each other, as shown in Figure 2.

The terminations of the sub-base teeth 15, 15, 15 are along the curved line 18.

An ornamental top 17 may be carried by the comb, if desired.

In the modification of the comb of my invention, shown in Figure 4, each of the base teeth 11 has an outward curve 19 and the sub-base teeth 20 are uncurved, the lower extremity of each sub-base tooth 20 being positioned slightly between two base teeth 11, 11. The base teeth and the sub-base teeth are staggered with respect to each other.

In the modification of my device, shown in Figure 5, both the base teeth 21, 21 and the sub-base teeth 22, 22 are straight, staggered with respect to each other and the lower extremity of each sub-base tooth is positioned slightly between two base teeth.

In the modification of my device, shown in Figure 6, the base teeth 23 and the sub-base teeth 24 are in parallel curves with respect to each other and staggered with respect to each other, the sub-base teeth 24 being curved at their upper extremity to form a curved jointure with the base 10.

It is evident that the sub-base may be as long as the base, if desired, and that the extremities of the sub-base teeth may terminate in a curve other than that shown in Figure 1, or may terminate in a straight line, and that the sub-base teeth need not be positioned between two base teeth.

I do not limit myself to the particular

size, shape, number, material, or arrangement, of parts, as shown and described, as these are given simply as a means for clearly describing my invention.

5. What I claim is:—

1. In a comb, in combination, a base, a row of undulated teeth carried by the base, a sub-base inwardly attached to the base and a row of teeth carried by the sub-base staggered with respect to the base teeth, a portion of each sub-base tooth being in the plane of the base-teeth and the extremity of the sub-base tooth being in front of the extremities of the base teeth.
- 10 2. In a comb, in combination, a curved base, a row of undulated teeth carried by the base, a sub-base inwardly attached to the base and a row of teeth carried by the sub-

base staggered with respect to the base teeth, a portion of each sub-base tooth being in the 20 plane of the base-teeth and the extremity of the sub-base tooth being in front of the extremities of the base teeth.

- 25 3. In a comb, in combination, a curved base, a row of undulated teeth carried by the base, a sub-base inwardly attached to the base and a row of undulated teeth carried by the sub-base staggered with respect to the base teeth, a portion of each sub-base tooth being in the plane of the base-teeth and the 30 extremity of the sub-base tooth being in front of the extremities of the base teeth.

Signed at New York city in the county of New York, and State of New York this 22nd day of May, 1924.

WILLIAM S. BECHTOLD.
